DESIGN FOR AN INSTRUMENT CASE

William Melas, Cynwyd, Pa., assignor to Cochrane Corporation, Philadelphia, Pa., a corporation of Pennsylvania

Application March 9, 1934, Serial No. 50,985

Term of patent 7 years

To all whom it may concern:

Be it known that I, WILLIAM MELAS, a citizen of the United States, residing at 176 Edgehill Road, Cynwyd, in the county of Montgomery and the State of Pennsylvania, have invented a new, original, and ornamental Design for Instrument Cases, of which the following is a specification, reference being had to the accompanying drawing, forming part thereof.

The figure is an isometric view of an instrument case, showing my new design.

I claim:

The ornamental design for an instrument case, as shown.

WILLIAM MELAS.
